FIG. 1 is a perspective view of an angled roof ventilation cap with a grill showing my new design;
FIG. 2 is a bottom perspective view, wherein the cylindrical opening is a through hole as shown in the cross-sectional view of FIG. 8 thereof;

FIG. 3 is a side view (opposite side view is mirror image) thereof;

FIG. 4 is a front view thereof;

FIG. 5 is a rear view thereof;

FIG. 6 is a top view thereof;

FIG. 7 is a bottom view thereof; and,

FIG. 8 is a cross-sectional view taken in the direction of arrows 8-8 in FIG. 4.
